Application September 14, 1937, Serial No. 71,609
In Great Britain May 13, 1937

Term of patent 14 years

To all whom it may concern:

Be it known that we, Frank George William King and Leonard John Lambourn, subjects of the King of Great Britain and residents of "Guy Harlings", Wyvern Road, Sutton Coldfield, county of Warwick, England, and Erdington, city of Birmingham, county of Warwick, England, respectively, have invented a new, original, and ornamental Design for a Bicycle Tire, of which the following is a specification, reference being had

to the accompanying drawing, forming a part thereof.

Fig. 1 is a perspective view, and Fig. 2 is a plan view of a section of a bicycle tire showing our new design.

We claim:

The ornamental design for a bicycle tire as shown.

FRANK GEORGE WILLIAM KING.
LEONARD JOHN LAMBOURN.
